CLAIM

The ornamental design for an inverter controller for electric motor, as shown and described.

DESCRIPTION

FIG. 1 is a front view of an inverter controller for electric motor, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a front, top and right side perspective view thereof.

The broken lines depict portions of the inverter controller for electric motor that form no part of the claim.

1 Claim, 7 Drawing Sheets
